UNITED STATES PATENT OFFICE

105,965

DESIGN FOR A SHOWCASE

John Rutledge McGhee, Washington, D. C.

Application February 23, 1937, Serial No. 67,813

Term of patent 14 years

To all whom it may concern:

Be it known that I, John Rutledge McGhee, a citizen of the United States, residing in Washington, District of Columbia, have invented a new, original, and ornamental Design for Showcases, of which the following is a specification, reference being had to the accompanying drawing, forming part thereof.

The figure is a perspective view of a showcase, showing my new design.

I claim:

The ornamental design for a showcase, as shown.

JOHN RUTLEDGE McGHEE.
